US0D1102822S

(12) **United States Design Patent** (10) **Patent No.:** **US D1,102,822 S**
(45) **Date of Patent:** **** Nov. 25, 2025**

(54) **OUTDOOR STOVE**

(71) Applicant: **HARVEST GRANDE INTERNATIONAL LLC**, Dallas, TX (US)

(72) Inventor: **Yongfeng Li**, Jiangmen (CN)

(73) Assignee: **HARVEST GRANDE INTERNATIONAL LLC**, Dallas, TX (US)

(**) Term: **15 Years**

(21) Appl. No.: **29/909,801**

(22) Filed: **Aug. 10, 2023**

(30) **Foreign Application Priority Data**

Jul. 18, 2023 (CN) 202330448481.2

(57) **CLAIM**

The ornamental design for an outdoor stove as shown and described.

DESCRIPTION

FIG. 1 is a perspective view of an outdoor stove showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the outdoor stove that form no part of the claimed design.

1 Claim, 8 Drawing Sheets
